(57) **CLAIM**

The ornamental design for a sensor port, as shown and
described.

DESCRIPTION

FIG. 1 is a front, top perspective view of a sensor port
showing our design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

In the drawings, the broken lines form no part of the claimed
design.
